CARPENTER'S PLANE

August A. Giacopini, Torrington, Conn.

Application May 6, 1949, Serial No. 91,745

2 Claims. (Cl. 145—14)

1

This invention relates to wood-working tools, and more particularly to a small hand plane adapted to be used in the household or elsewhere for smoothing and shaving surfaces.

One object of this invention is to provide a device of the above nature which is composed of a minimum number of parts, and which will involve no precise machine operations in its manufacture.

A further object is to provide a device of the above nature which will be simple in construction, inexpensive to manufacture, easy to adjust and manipulate, compact, dependable, ornamental in appearance, and very efficient and durable in use.

With these and other objects in view, there has been illustrated on the accompanying drawing one form in which the invention may conveniently be embodied in practice.

In the drawing,

Fig. 1 is a side view of the improved plane, partly broken away to show the blade and its mounting means.

Fig. 2 is a perspective view of the same, partially broken away.

Fig. 3 is a front view thereof.

Fig. 4 is a rear view thereof, a portion of the handle being broken away to show the adjusting screw.

Referring now to the drawing in which like reference numerals denote corresponding parts throughout the several views, the improved plane is indicated generally by the numeral 10, and comprises a flat sheet metal sole plate 11 which is turned upwardly at its opposite sides so as to form parallel vertical side walls 12, 13.

The sole plate 11 and the adjacent lower portions of the side walls 12, 13 are provided with a transverse slot 14 through which a lower cutting edge 15 of a blade 16 is adapted to extend. The blade 16 is slidably supported in an inclined position upon a pair of inclined lower ears 17, 18, which are struck inwardly from opposite portions of the side walls 12, 13, and a cross bar 19 which has reduced ends 20 secured in the upper portions of said side walls.

In order to hold the blade 16 securely in place, provision is made of a clamping plate 21 having a downwardly offset lower end 22 which is engaged beneath a pair of upper ears 23, 24 struck inwardly from the side walls 12, 13, and which bears against the upper surface of said blade 16 a short distance forwardly of the lower ears 17, 18.

An upper portion of the clamping plate 21 with a transverse blade slot, an inclined blade

carries a thumb screw 25 which is adapted to bear against the upper surface of the blade 16, whereby the clamping plate 21 may be actuated to exert a powerful lever action against the upper ears 24 and thus lock the blade 16 in operating position against the lower ears 18 and the cross bar 19.

The clamping plate 21 is extended rearwardly and upwardly beyond the thumbscrew 25 so as to form a convex handle or shield 21a which will serve as an abutment for the user's hand during operation of the plane 10, thus permitting an efficient operating force to be applied to the plane without discomfort to the user.

15 The depth of the cut which may be made by the cutting edge 15 is adapted to be regulated by means of an adjusting screw 26 which is disposed below the handle 21a and which is threaded downwardly through a central aperture in the cross bar 19 in a direction parallel to the blade 16. The lower end portion of the adjusting screw 26 is provided with a peripheral groove 27 which is interengaged by the lower end of a forked lug 28 centrally secured upon the lower 20 side of the blade 16.

Thus, it will be seen that the blade 16 may easily be moved in a longitudinal direction so as to adjust the position of the cutting edge 15 merely by turning the knurled head of said adjusting screw 26.

30 It will be understood, however, that the thumb screw 25 will first be loosened to permit adjustment of the blade 16, and will be tightened when the adjustment is completed. The thumbscrew 25 is adapted to actuate the clamping plate 21 so as to hold the blade 16 securely against change of adjustment at all times when the plane 10 is in use.

While there has been disclosed in this specification one form in which the invention may be embodied, it is to be understood that this form is shown for the purpose of illustration only, and that the invention is not to be limited to the specific disclosure, but may be modified 40 and embodied in various other forms without departing from its spirit. In short, the invention includes all the modifications and embodiments coming within the scope of the following claims.

Having thus fully described the invention, 50 what is claimed as new, and for which it is desired to secure Letters Patent, is:

1. In a carpenter's plane, a sheet metal sole plate having a pair of parallel upturned side walls integral therewith, said sole plate being provided

located between said side walls and having a bottom cutting edge freely disposed within said slot, means for supporting the lower surface of said blade comprising a pair of lower ears struck inwardly from said side walls and an upper cross-bar rigidly secured between said side walls, a pair of upper ears struck inwardly from said side walls and spaced from said lower ears, a blade clamping plate provided with a downwardly offset lower portion having a shoulder engaged by 10 said pair of upper ears, the lower end of said clamping plate engaging said blade adjacent the cutting edge thereof, said clamping plate having a thumb screw threaded therein and engaging the upper portion of said blade, and screw 15 means threaded into said cross-bar and loosely engaging a depending fork on said blade for longitudinally adjusting said blade.

2. The carpenter's plane as defined in claim 1, in which said clamping plate has a rearwardly- 20 extending downwardly concave shield to protect the carpenter's hand during use.

AUGUST A. GIACOPINI.
